[57] **CLAIM**

The ornamental design for a base member for the mounting of machine components, as shown and described.

DESCRIPTION

FIG. 1 is a perspective view of a base member for the mounting of machine components, showing our new design;

FIG. 2 is a top plan view thereof;

FIG. 3 is a front elevational view thereof;

FIG. 4 is right side elevational view thereof;

FIG. 5 is left side elevational view thereof; and,

FIG. 6 is a rear elevational view thereof.

—FIG. 1

—FIG. 2

—FIG. 3

—FIG. 4

—FIG. 5

—FIG. 6
